(57) **CLAIM**

The ornamental design for a cushion for nasal mask as shown and described.

DESCRIPTION

FIG. 1 is a perspective view showing a cushion for nasal mask design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The broken lines illustrate portions of the cushion for nasal mask that form no part of the claimed design.

1 Claim, 2 Drawing Sheets
